UNITED STATES PATENT OFFICE.

ADAM W. SEVERANCE, OF PORTLAND, OREGON, ASSIGNOR TO GOLD SAVING MACHINE CO., OF PORTLAND, OREGON.

MACHINE FOR RECOVERING PRECIOUS-METAL CONCENTRATES.

Application filed August 18, 1924. Serial No. 732,704.

My invention is intended for use in the recovery of precious metal concentrates, and is adapted particularly, for use in arid countries where all year mining operations are unknown at the present time because of a lack of necessary water. In my invention I have so constructed the machine that the water may be used over and over again. I am aware that in former machines the agitation of the water is caused by the pumping of air under pressure and the same is released, under pressure, at or near the bottom of the working basin. But in machines of this kind the evaporation caused by the release of the air from under pressure was great. I have found that certain flotation agents and other chemicals may be added to the water that are of great benefit in the scouring of the precious metals to be recovered that is not practical where air is used as an agitating means.

Certain other new and novel elements of my machine reside in the construction of the bottom of my working tank, and in the recovery, or ore valve, as well as in the agitating bars that are carried through the liquid that serve to abrade the materials to be treated.

In my arrangement for the circulation of the water, which may carry chemicals or bleaching agents for the renewing, or refreshing of the surfaces or faces of the material to be concentrated I create a machine that has in effect the essential elements for the recovery of the precious metals by the flotation process. The pumping of the liquids back and the discharging of the same at or near the bottom of the settling and concentrating tank makes possible the use of a limited amount of the water and of the added materials to that of the water to provide a suitable vehicle to accomplish the desired results.

In the drawings—

Fig. 1 is a side elevation of the assembled machine showing the arrangement and detail of the parts composing the same.

Fig. 2 is a partial sectional view of the outlet end of the machine.

Fig. 3 is an enlarged side elevation of the feeding end of the machine.

Fig. 4 is a partial sectional, end view taken on line 4—4 of Fig. 2 looking in the direction indicated.

Fig. 5 is a sectional end view taken on

line 5—5 of Fig. 2 looking in the direction indicated; this view is made to illustrate the bottom construction.

Fig. 6 is a sectional end view, made large, of a part of the bottom section; and more particularly to show the liquid bearing pipes.

Fig. 7 is an end sectional view of the ore valve here shown as a segment of a circle, and which is of a different construction than that used in the other views.

Fig. 8 is a detailed fragmentary view of the agitating bars and the means for mounting the same.

Fig. 9 is a detached side elevation of the side of the machine made to illustrate the operating lever for the ore valve.

Fig. 10 is a bottom plan view of the machine looking upward from below the bottom, and made to show the operating method for the ore valve and the mechanism for imparting a side motion to the body portion of the machine.

Fig. 11 is also a plan view of one end of the machine and the trunnion supports are here shown in dotted position.

Like reference characters refer to like parts throughout the several views—

1 is the lower member of the base of the machine here shown as a rolled shape which is connected to a top member of like material as shown at 3 the same being connected by upright members 2. For convenience in transportation I have made the frame and the tank in sections that may be reassembled. I have here shown a machine in two sections and have provided flanged bolting members 5 and 6 at which point the two ends may be reunited into one rigid member. The liquid tank may also be made in two sections 7 and 8 and united in the ends by suitable means. I have purposely shown a machine made of two sections but I do not wish to be limited to a two section machine and have here shown a two section machine for the purpose of illustration and description, but in the larger sized machines it may become necessary to make machines of more sections.

When the machines are being operated in an arid country and water is scarce, a settling basin 9 is provided into which the water drains and from which it is pumped back into the machine. A suitable pumping unit 10 is provided that pumps the water from

the settling basin 9 through pipe 11 into a header 12, having a suitable air cushion receiver 13 mounted thereupon. A blow off cock 14 is provided at the top of the cushion receiver. Individual pipes lead from the header to the distributing triangular shaped pipes that run lengthwise of the machine at the bottom of the flat bottomed tank 7. These triangular pipes have outlets at each side adjacent the bottom that discharge the water under pressure to create an agitation of the liquids and of the solids that have gravitated to the bottom of the tank. These pipes are made triangular in shape and are laid parallel to each other, as is shown in detail in Fig. 6 leaving a space between the same to permit of the passage of a rigid member therebetween. The solid matter gravitates within this space and the passage of the rigid member down this passageway creates a grinding action upon the individual particles that tends to renew and polish the surfaces of the particles to the extent that those of highest specific gravity and which are of some magnitude in size will be carried along to the ore valve outlet. The discharging of the liquid under pressure through the openings 16 creates a great agitation in the deposited material, and the fine material such as gold and the like that is so deposited may be carried upward and be screened off as in the flotation process. The liquids being pumped and so discharged is made to carry those essential elements necessary in the flotation process for the recovery of those precious metals susceptible of being saved thereby.

The tank members have a flat bottom 17 that has disposed thereupon a renewable wearing plate 18 having upturned edges disposed against the sides of the tank as shown at 19. The triangular shaped water conduits 23 are secured to the bottom wearing plate 19 by suitable means and are arranged in substantially parallel rows. The object for making these pipes or conduits in this shape is that it permits the making of the bottom members flat and the renewal of individual conduits. These triangular pipes are subjected to great wear because of the abrasive material being treated in substantial quantity and because of the fact that larger quantities are transported in certain parts than in others it is highly desirable that these members may be taken out as individual units.

An endless chain 20 is driven and traverses a course about sprockets 25 and 26 and passes about the idler sprocket 27. Disposed, at spaced intervals, about the chain are cross bars 21. A flexible connection is provided between the cross bar 21 and the drag bar 28. Lug grinders 29 are attached to the cross bar 28 in spaced relationship, corresponding to the spaces between the wa-

ter conduits 23. The length of these lugs is equal to the depth of the valleys between the water conduits, and the width of each is somewhat less than the distance between the edges of the water conduits. The weight of these cross bars is sufficient to create pressure upon these grinding lugs. The agitation caused by the incoming water washes the deposited aggregate and the particles that are sufficiently fine will be suspended in the liquid within the tank, the remainder will be ground between the lugs and the contacting surfaces. Much of the precious metal that is to be saved by this machine has lain exposed to the elements for long periods and the same becomes oxidized upon its surfaces, making its recovery more difficult. The purpose of this grinding action is to create bright surfaces upon the materials to be recovered.

These endless chains are two or more in number and the sprockets about which they run are mounted upon shafts journaled within the frame structure. The power unit for operating the same may be mounted upon the bed of the machine, or the same may be secured from some source outside; in that event a power shaft 30 is provided having a pulley fly wheel 31 mounted thereupon. Mounted upon this shaft is a driving sprocket with which chain 32 is engaged and chain 32 also engages with a sprocket 33^a mounted upon shaft 33^a. In machines of the larger capacity I have found best results are obtained by these driving chains being of comparatively short lengths, for the wear tends to increase the length of the chain and defective driving is the result in chains of long lengths. A second chain 33 imparts rotation to the sprocket 34^a mounted upon the shaft 34. Mounted upon the shaft 34 is a second sprocket driving chain 35 which imparts rotation to shaft 36 mounting the sprockets for driving the drag chain 20. The pillow block 37 supporting the bearings for the shaft 36 is mounted upon the sloping bracket supports 39 and as the drag chain becomes loose from wear the chain is tightened by the application of pressure upon the screw 38 which is attached to the pillow block. The screw 38 is held in position by the bracket 39. The bars 21 serve also to drag the tailings from the machine up the incline 40 and deposit the same in the tailing chute 41.

The incoming materials to be treated in the machine are deposited in a hopper 42 having a removable screen bottom 43.

A vanner like movement is imparted to the machine treating members, and is accomplished by an eccentric 44 mounted upon the main drive shaft 30, an eccentric strap 45 is disposed about the eccentric and imparts an oscillating movement to the connecting rod 46. The tank structure is sup-

ported upon axles 47 upon which trunnion wheels 48 are mounted. These trunnion wheels 48 are mounted upon tracks that do not run parallel with the body structure of the machine, this is best shown in Fig. 11. Thus when an oscillating movement is imparted to the tank structure by the eccentric a lateral motion is imparted to the tank by the action of the trunnion wheels upon the tracks, thus a vanner motion is imparted to the tank structure.

Located near the discharge end of the machine is an ore valve made of the gate type and as the material that has gravitated to the bottom and is not held in suspension in the liquid is passed over this valve, the heavier particles are deposited within this depression and are trapped through the opening when the valve is opened. The valve is opened at regular intervals by the action of the lever 49, one end of which is secured to the frame of the machine. This lever has a slot 49^a on its fixed end and is clamped in position by the thumb screw 49^b to the frame structure. Opposite the slotted end of the lever 49 is a right angle bend 49^c that is adapted to engagement in a suitable hole in the rod 50. The rod 50 is pivoted about pin 51 and is attached to the slide, or gate valve at 53. The valve blade 54 has contact with the seat 55 for a sufficient distance to compensate for the slot in the lever 49, and by the proper setting of the valve in relation to the location of the slot and the clamped position of the set screw 49^b the desired opening of the valve may be obtained.

At times it may become necessary to provide for the manual manipulation of this valve; this is accomplished by the disengagement of the lever 49 and placing the same in the dotted position as shown in Fig. 9. The rod 50 may then be used as a hand lever and the same can then be operated at desired intervals. The deposited materials that drop through the valve opening are released into the chute 54^a and from there deposited into desired receptacles.

The depth of the tank structure will depend upon the kind of materials to be treated and upon the character of treatment to be given, but I have here shown in detail the character of machine that I have found most practical in the recovery of the precious metals having a relatively high specific gravity.

Having thus described my invention I wish to make the following claims therefor—

1. A machine for recovering precious metal concentrates, comprising a sectional frame, a flat bottomed tank mounted within the frame, means for imparting a vanner action to the tank, triangular conduits arranged in substantially parallel lines upon the bottom of the tank said triangular conduits adapted to discharge liquid under

pressure from each side near the floor of the tank, means for admitting materials to be treated into the tank, means for grinding and polishing the materials while being treated, and discharging means for the treated materials. 70

2. A machine for recovering precious metal concentrates, comprising a sectional frame, a flat bottomed tank mounted within the frame, means for imparting a vanner motion to the tank, triangular conduits arranged in substantially parallel lines upon the bottom of the tank said triangular conduits adapted to discharge liquid under pressure from each side near the floor of the tank, means for admitting materials to be treated into the tank, means for grinding and polishing the materials while being treated, and discharging means for the treated materials. 75

3. A machine for recovering precious metal concentrates, comprising a structural steel frame, a track supported within the frame, trunnion wheels mounted on axles adapted to cooperate with the track, a tank structure, having a flat bottom, mounted on said axles, means for imparting a vanner movement to said tank, triangular conduits arranged in substantially parallel lines upon the bottom of the tank, said triangular conduits adapted to discharge liquid under pressure from each side near the floor of the tank, endless chains adapted by means of cross bars, to drag the material to be treated, from the inlet end to the discharge end of the tank, flexibly connected drag bars carrying lug grinders attached to cross bars, lug grinders adapted to impart a grinding action on the material to be treated, means for removing the material of high specific gravity, and means for removing the tailings. 95

4. A machine for recovering precious metal concentrates, comprising a frame structure, a tank structure adapted to maintain liquid therein, mounted within the frame and means for imparting a shaking motion to the tank structure, triangular shaped conduits arranged in parallel rows adjacent the inner bottom surface of the tank, endless drag chains adapted to being traversed the length of the tank and having transversely disposed cross bars attached thereto, flexibly connected drag bars carrying lug grinders attached to the cross bars, said lugs adapted to impart a grinding action to the material to be treated, means for depositing screened materials to be treated within the tank, and means for removing the materials of high specific gravity in advance of the removal of the tailings. 110

5. A machine for recovering precious metal concentrates comprising a frame structure, a tank structure adapted to main- 125

130

tain liquid therein, mounted within the frame, means for imparting a shaking motion to the tank structure, triangular shaped conduits arranged in parallel rows adjacent the inner bottom surface of the tank, means for discharging water under pressure from said triangular conduits, endless drag chains adapted to being traversed the length of the tank and having transversely disposed cross bars attached thereto, flexibly

connected drag bars attached to the cross bars, lug grinders secured to said drag bars, and adapted to impart a grinding action on the material to be treated, means for depositing screened materials to be treated within the tank, and means for removing the materials of high specific gravity in advance of the removal of the tailings at one end of the tank. 15

ADAM W. SEVERANCE.
